UNITED STATES PATENT OFFICE.

CHARLES ERNEST JONES, OF CHICAGO, ILLINOIS.

DESIGN FOR AN ORNAMENT FOR BRACKET-BACKS.

51,384.

Specification for Design.

Patented Oct. 16, 1917.

Application filed August 18, 1917. Serial No. 187,024. Term of patent 3½ years.

To all whom it may concern:

Be it known that I, CHARLES ERNEST JONES, a citizen of the United States, residing at Chicago, in the county of Cook and State of Illinois, have invented a new, original, and ornamental Design for an Ornament for Bracket-Backs, of which the following is a specification, reference being had to the accompanying drawing, wherein—

Figure 1 is a side view, and

Fig. 2 is a front elevation of an ornament for bracket backs showing my new design.

I claim as my invention:

The ornamental design for an ornament for bracket backs, as shown.

CHARLES ERNEST JONES.
